UNITED STATES PATENT OFFICE.

CHARLES W. CELL, OF RIVERSIDE, CALIFORNIA.

FASTENING DEVICE.

Application filed June 25, 1923. Serial No. 647,736.

This invention relates to fastening devices, and more particularly to means for fastening two abutting members to each other.

5 An object of the invention is to provide a fastener for the side section of stake racks, wagon bodies, tanks, gates and the like in which two members arranged in alignment with each other are to be joined or connected, said fastener consisting of a rod pivotally connected to one section and a member pivotally mounted on the other section, said pivotally mounted member having an eccentric slot to receive the end of said 10 rod, whereby said sections are drawn together when the pivoted member is turned to a locked position.

A further object of the invention is the provision of a fastener of this type which 20 may be readily closed and released.

A further object is the provision of a fastener of simple construction and relatively few parts.

In the accompanying drawings, I have 25 shown one embodiment of the invention. In this showing:

Figure 1 is a side elevation of two members, such as the side sections of the stake rack showing the fastener applied,

30 Figure 2 is a plan view,

Figure 3 is a horizontal sectional view on line 3—3 of Figure 1,

Figure 4 is a vertical sectional view on line 4—4 of Figure 1, and,

35 Figure 5 is a detail perspective view of the pivotally mounted member.

Referring to the drawings, the reference numeral 1 designates one section of a stake rack and 2 an adjacent section, the two 40 sections being adapted to be secured to each other. A rod 3 is pivotally mounted in one of said sections. As shown, the rod is provided with an offset end 4, passing through an opening in the section 1. The inner end 45 of the rod is adapted to receive a nut 5, and this nut is arranged in a recess 6 on the inner side of the section 1 so as to be flush with the surface. A wear plate 7 may be arranged beneath the rod. As shown, the 50 rod is inclined outwardly, as at 8, so that its free end 9 is slightly spaced from the faces of the sections. This end is provided with an offset portion 10, as shown.

55 A member 11 is pivotally mounted on the other section of the stake rack. As shown, this member is provided with an opening

adapted to receive a screw or pin 12, forming a pivot. The pivotally mounted member is provided with a slot or recess 13 parallel to its outer face and is further provided 60 with a transverse slot 14, extending from the rear face to the slot 13.

In operation, with the parts in dotted line position shown in Figures 1 of the drawings, and the slot 14 extending upwardly, the rod 3 is moved downwardly with the offset end of the rod in the slot 13 and the body portion in the slot 14. When the offset end engages the bottom of the slot 14, further downward movement is prevented. 70 The pivoted member is then turned downwardly to the full line position, swinging the slot 14 to a substantially horizontal position as shown in Figure 5 of the drawings, and exerting a pull on the rod 3, which 75 draws the members 1 and 2 together and forms a lock to retain them in such position. To disengage the members 1 and 2, the pivotally mounted member is moved to the dotted line position and the rod 3 lifted 80 from the slot.

While I have illustrated the invention as a fastener for the sides of stake racks, it is apparent that it may be employed in any construction where a pair of members are arranged in alignment with each other, with the ends of the members abutting as a fastener to secure such members to each other. 85

It is to be understood that the form of the invention herewith shown and described is to be taken as a preferred example of the same, and that various changes in the shape, size, and arrangement of parts may be resorted to without departing from the spirit 90 of the invention or the scope of the subjoined claims. 95

I claim:

1. A stake rack fastener comprising a member pivotally connected at one end to one section of the stake rack, the other end of said member having a portion projecting beyond the end of the section parallel to the stake rack, said projecting portion being provided with an end portion bent at right angles thereto, and a locking member pivotally connected to the adjacent section of the rack, said locking member being provided with a pair of spaced arms parallel to the stake rack providing therebetween a longitudinal slot in the same plane as the projecting end of said pivoted member and into which the projecting end of said pivoted 110

member is adapted to be inserted, one of said arms being provided with a transverse open ended slot adapted to removably receive the bent end of said pivoted member, said projecting end being adapted to swing from unlocked to locked position across a line between the pivots of said members, and being adapted to engage against the bottom of said longitudinal slot to prevent movement of said locking member beyond normal locked position.

2. A stake rack fastener comprising a member pivotally connected at one end to one section of a stake rack, said member projecting beyond the end of the section parallel to the stake rack and being provided with an end portion bent at right angles to the projection portion and extending inwardly toward the stake rack, a locking member arranged against the adjacent portion of the stake rack, said locking member being normally vertical and having a normally horizontal upper face portion adapted to be arranged beneath and to contact with the

projecting portion of said pivoted member, 25 said locking member being further provided with a pair of upstanding arms arranged parallel to the stake rack, and upon opposite sides of said horizontal upper face portion and between which the projecting portion of 30 the pivoted member is adapted to be inserted, one of said arms contacting with the stake rack and having an open ended transverse slot adapted to receive the bent end of 35 said pivoted member, said locking member being further provided beneath said arms with a normally depending handle, and a pivot pin passing through the arm arranged against the stake rack and extending thereinto, said pivot pin being arranged above 40 the projecting portion of said pivoted member when said projecting portion is in contact with the horizontal face portion of said locking member.

In testimony whereof, I affix my signature.

CHARLES W. CELL.
